UNITED STATES PATENT OFFICE.

OSKAR FREIBERG, OF GAUTZSCH, NEAR LEIPZIG, GERMANY.

SPARKING PLUG.

1,106,703.

Specification of Letters Patent. Patented Aug. 11, 1914.

Application filed September 19, 1913. Serial No. 790,833.

To all whom it may concern:

Be it known that I, OSKAR FREIBERG, a subject of the German Emperor, and resident of Gautzsch, near Leipzig, Germany, have invented certain new and useful Improvements in Sparking Plugs, of which the following is a specification.

Hitherto, sparking plugs have become known, in which at the same time sparks are formed at several places, for which purpose either one or both spark contacts terminate in several contact points, or the contact wire is interrupted at certain places and at its other parts surrounded by insulating material, these arrangements having the drawback that at the gaps between the insulating material dirt, oil or the like may settle, or the distance between the contact points becomes gradually larger and larger owing to burning of the contact points until a formation of sparks does not happen at all. In another type of sparking plug between the spark contacts connected with the circuit one or more auxiliary contacts are arranged with the object to effect a formation of sparks between the main and auxiliary contacts upon the voltage having become too weak for a formation of sparks between the main contacts. It has also been proposed to arrange one row of auxiliary contacts between the main contacts, which in some cases are all disposed in circular fashion. All these hitherto known sparking plugs have the drawbacks that the formation of sparks is not absolutely reliable, or that the sparks are not always vigorous enough for effecting under all circumstances a reliable ignition of the gas mixture in motors, by the latter being frequently difficultly inflammable so that with a weak spark formation an ignition of the gas mixture may not happen. All these drawbacks are overcome by the subject matter of the present invention by offering to the formation of sparks not one way only but a large collection of ways, whereby a perfectly reliable ignition is obtained. Owing to its reliable action, the improved sparking plug is particularly adapted for use in connection with internal combustion motors for motor-cars, flying-apparatus, and the like.

The invention essentially consists in arranging between the main contacts connected with the circuit a large number of cross-wise arranged parallel rows of auxiliary contacts of particularly appropriate form

in a non-conductive way and at distances of a spark from each other in such a way that a large number of ways is offered for the formation of sparks, whereby at each ignition a large number of sparks are safely obtained.

The accompanying drawing shows the subject matter of the present invention.

Figure 1 is a central longitudinal section through a sparking-plug. Fig. 2 is an underside plan view of the same; Fig. 3 is a rear view of a sparking plug of modified construction, and Fig. 4 is a longitudinal section through the latter on the line A—B of Fig. 3.

Referring to Figs. 1 and 2.—The construction shown is particularly adapted for use in connection with motor-cars, flying-apparatus and the like, its outer shape being similar to those hitherto employed. The outer body *a* of iron or other metal is, as usual, provided with lower screw-threads for its being screwed into the cylinder wall, and it serves for the reception of an insulating body *b* of porcelain or the like. At the inner end of the latter, contacts *c* of prismatic or other cornered shape are so arranged that the corners of the contacts are separated from the corners of the adjacent contacts for the distance of a spark, so that each contact is allowed to form at a time a plurality of sparks in several directions. One of said contacts is connected with the lead *d* and another one with the lead *e* of the circuit. The lead *e* is connected with the metal body *a*, which in a way known in the art receives its conductive connection by connection of the motor casing to the circuit, while the second lead *d* is non-conductively led through the porcelain body *b* and connected with the circuit by a contact-screw. According to the size of the motor, or to the quantity of the volume of the gas mixture to be ignited, and according to the easier or more difficult ignition of the gas mixture, the number and arrangement of the spark contacts *c* can be determined.

Referring to Figs. 3 and 4, the construction shown is particularly adapted for large motors, for which purpose a very large number of contacts *c* is arranged in several rows beside each other. In the construction, the auxiliary contacts *c* and the main contacts *d* and *e* connected to the circuit are inserted in a plate *g* of porcelain or the like insulating material, which may be further fixed on a

base plate *h*, which has holes *i* for the fixing-screws and which may be made either also of insulating material or of metal, the leads to the contacts *d* and *e* being in the latter case insulated from the plate *h*. The supply of current to the contacts *d* and *e* may be effected through terminals *f*. Obviously, the construction of the sparking plug may be further modified to suit requirements.

13 I claim:

In a sparking plug, the combination of

main contacts connected with the circuit, and a large number of crosswise arranged parallel rows of auxiliary contacts of prismatic shape between the latter arranged at 15 sparking distances from each other, substantially as and for the purpose set forth.

OSKAR FREIBERG.
